UNITED STATES PATENT OFFICE.

STUART ARCHIBALD BROWN, OF NEW YORK, N. Y.

STAIR-ROD AND SECURER.

SPECIFICATION forming part of Letters Patent No. 744,472, dated November 17, 1903.

Application filed April 14, 1903. Serial No. 152,532. (No model.)

To all whom it may concern:

Be it known that I, STUART ARCHIBALD BROWN, a citizen of the United States, and a resident of the city of New York, borough of the Bronx, in the county and State of New York, have invented new and useful Improvements in Stair-Rods and Securers, of which the following is a full, clear, and exact description.

10 This invention relates to stair-rods and securers; and it consists, substantially, in the construction, organization, and combinations of parts hereinafter particularly described and claimed.

15 Though applicable to wooden stairs, my improvements are especially intended for use in connection with stairs constructed of hard materials—such as marble or iron, for instance—and into which it is impossible to drive or insert tacks or the like for securing the carpet or covering in place upon the stairs.

The principal object of the invention is to overcome numerous disadvantages and objections common to many devices hitherto de-

25 vised for a similar purpose and also to provide a combined stair-rod and securer which is thoroughly effective and reliable in operation and which possesses the capacity for long and continued service, besides comprising few

30 parts not liable to get out of order.

A further object is to provide a device of the character referred to which may be applied to its purpose in a manner to be concealed from view and also to simplify the construction and operation of the device, as will presently appear.

The above and additional objects are attained by means substantially such as are illustrated in the accompanying drawings, in

40 which similar characters of reference indicate corresponding parts in all the views.

Figure 1 is a perspective view of a part of a staircase, showing my improved stair-rod and securer employed in connection therewith.

45 Fig. 2 is a vertical transverse sectional view taken about on the line 2 2 of Fig. 1. Fig. 3 is a front elevation of the device, showing the construction and organization thereof more clearly; and Fig. 4 is a transverse sectional

50 view on the line 4 4 in Fig. 3.

Before proceeding with a more detailed description it may be stated that in the embodi-

ment of my improvements herein shown I preferably employ a device which is adapted for the securing in place upon stairs of carpetings or coverings of different widths, it being understood that one of the said devices is employed in connection with each riser and tread of the stairs. The device is provided with means disposed at suitable distances apart which in the use of wooden stairs enable the carpet to be positively secured to the tread at different points thereof and also with means whereby the carpet is prevented from rucking up between such points, thereby enabling the carpet to be held evenly and smoothly in place. The device is also adapted for use in connection with stair-risers of different heights, and while I have herein represented a certain preferred construction and organization of parts constituting the device it will be understood, of course, that I am not limited to the precise details thereof in practice, since immaterial changes therein may be resorted to coming within the scope of my invention.

Specific reference being had to the accompanying drawings, 1 represents an ordinary staircase constructed of stairs having the usual risers 2 and treads 3, and 4 indicates a carpet or covering for said stairs, the same being of any desired width, as will presently appear. In order to securely fasten the said carpet or covering 4 evenly and smoothly in place upon the stairs, I preferably employ a strip 5 of metal or other suitable material, which rests upon and engages the upper surface of the carpet above one of the treads, and I also preferably construct the said strip of two or more sections, one lapping the other lengthwise, as shown, one of said sections being provided with a longitudinal slot 6 and the other with a screw 7, working in said slot and having thereon preferably a wing-nut 8, by which to tightly secure the sections in adjusted relations thereof, it being apparent from the construction described that the said strip is thus rendered adaptable to stair carpetings or coverings of different widths. With wooden stairs in order to provide means for positively securing the carpet or covering to each tread 3 at different longitudinal points thereof and beneath the tread next above the same I provide the strip 5 (or each of its sec-

tions) at intervals of its length with a rod 9, which is threaded at 10 for a suitable distance from its upper end and is pointed at its lower end 10^a, said rod being preferably flattened 5 at 11 and pivotally secured to one side of the strip (or section thereof) in any suitable way, as by means of a pin 12, held in place by a nut 13. Each of these rods is provided on the threaded portion thereof with a rotatable 10 member or sleeve 12^a, which is adjustable on the rod and formed with barbs or prongs 12^b for biting or taking into the under side of the projecting edge 12^c of the tread, as and for the purpose presently explained. Thus it 15 will be seen that the said rods may be taken hold of by the hands and swung or turned on their pivots in such manner as to cause the pointed ends thereof to pass through the material of the carpet and bite or take slightly 20 into the material of the tread, whereupon the carpet may be stretched transversely to any desired extent, all of which is clearly apparent. After thus stretching the carpet the pointed ends of said rods may be allowed to 25 remain thus engaged, whereupon by properly adjusting the said members or sleeves 12^a on the rods by means of the nuts 14 at the lower ends thereof the said barbs or prongs 12^b of each member or sleeve may be forcibly projected into the material of the tread above, and in this way both the carpet and the entire device will be securely held in place.

It may be stated that in applying the devices as above explained the operation is 30 started at the bottom of the stairs and proceeded with upwardly, and thus it will be seen that the riser portions of the carpet may be carried to proper position successively and in a manner to entirely conceal the devices 35 from view, each device occupying a position between each of such portions of the carpet and the corresponding or adjacent riser proper, as shown. In the case of stairs constructed of hard material—marble or iron, for 40 instance—it is impossible, of course, to cause the points and barbs of the device to take into the material of the stairs, as above explained with reference to wooden stairs; but by providing a fold 15 in the carpet at or near 45 the inner edge of each tread substantially an equal purchase is obtained for said rods in effectively tightening and securing the devices and carpet in place. Obviously the strip 5 is securely held down across the carpet 50 in a manner to prevent the latter from

rucking or rising up between the rods. An additional advantage is had from pivoting the rods 9 to the side of the strip 5 in that in the shipment or transportation of the device in quantities said rods may be turned practically alongside said strip, and thus not take up so much space. Other advantages also exist which it is not deemed necessary to herein specifically refer to. 60

Having thus described my invention, I 65 claim as new and desire to secure by Letters Patent—

1. A stair-rod and securer, comprising a strip for engaging a carpet longitudinally of the tread of a staircase, pointed rods pivotally attached to said strip, and an adjustable device on each rod constructed to engage a part of the under surface of the tread next 70 above, said strip being formed of a plurality of sections having means for securing them 75 together.

2. A stair-rod and securer, comprising a strip for engaging a carpet longitudinally of the tread of a staircase, pointed threaded rods pivotally attached to said strip, and a sleeve 80 and an adjusting-nut therefor working on each rod, said sleeve being provided with prongs adapted to engage a part of the under surface of the tread next above.

3. A stair-rod and securer, comprising strip sections for engaging a carpet longitudinally of the tread of a staircase, means for holding said strips in adjusted relation lengthwise of each other, pointed threaded rods pivotally secured to said sections, and an adjusting- 85 sleeve working on each rod, and provided at an end thereof with means for engaging a part of the under surface of the tread next above.

4. A stair-rod and securer, comprising means for engaging a carpet longitudinally 90 of the tread of a staircase, said means being adjustable to carpets of different widths, and means engaging the tread next above, for fastening both the entire structure and carpet 95 in place, said latter means being adjustable 100 in conformity with risers of different heights.

In testimony whereof I have signed my name to this specification in the presence of the subscribing witnesses.

STUART ARCHIBALD BROWN.
